Primary Examiner — Susan Bennett Hattan*Assistant Examiner* — Brett Miller(74) *Attorney, Agent, or Firm* — McClure, Qualey & Rodack, LLP(57) **CLAIM**

The ornamental design for a cooking grate with extended handles, as shown and described.

DESCRIPTION

FIG. 1 is a perspective view of my new design for a cooking grate with extended handles, shown here installed in a barbecue grill;

FIG. 2 is a top plan view thereof;

FIG. 3 is a bottom plan view thereof;

FIG. 4 is a right side elevational view thereof, the left side being a mirror image thereof; and,

FIG. 5 is a front elevational view thereof, the rear being a mirror image thereof.

The broken lines depict unclaimed environment and form no part of the claimed design.
